UNITED STATES PATENT OFFICE.

JOSEPH MOSES WARD KITCHEN, OF EAST ORANGE, NEW JERSEY.

METHOD OF FUEL FEEDING AND COMBUSTION CONTROL.

1,331,774.

Specification of Letters Patent.

Patented Feb. 24, 1920.

No Drawing.

Application filed March 11, 1918. Serial No. 221,808.

To all whom it may concern:

Be it known that I, JOSEPH MOSES WARD KITCHEN, a citizen of the United States, residing in the city of East Orange, county of 5 Essex, and State of New Jersey, have invented new Methods of Fuel Feeding and Combustion Control, of which the following is a specification.

The present invention is an advance on 10 the ideas described in my Patents Nos. 1,094,390, and 1,127,777; and has for one of the objects the utilization of cinders or coke; and fine fuel dusts that have usually been thrown away. Another object is to secure 15 temporarily a decrease in and later, an automatic increase in the rate of combustion in house heating and power producing plants, and to avoid burning fuel that has been fed to a furnace when such burning is not 20 needed, as well as to avoid burning fuel under a strong, rapid draft, which is usually a wasteful draft, at certain hours when increased heat transmission is desired quickly.

It is an old practice to "bank" fires with 25 ashes or earth which clog the fuel mass, during those hours when the production of heat by the burning of fuel is not desired. It is also an old practice to reclaim cinders, and burn them as an economical procedure, 30 either wet or dry. The economy of that procedure is frequently problematical, involving as it does, dust production in the process of reclamation; and also, because cinders have little or no easily volatizable burnable 35 constituents; and hence, are not so readily consumed as those fuels which contain a larger amount of the more volatile matters.

In the usual methods of burning coal in 40 household heating devices, at or prior to bed-time, a very considerable amount of fuel is fed into the heating device to keep the fire going until the time of arising from bed in the morning, provision usually being made in the construction of the heating device to contain a sufficiently thick bed of 45 fuel to maintain active combustion through the night. The result is, that a very considerable amount of carbon monoxide gas and other gaseous matters, through reaction are 50 evolved in, or driven off from the upper layers of the fuel-mass by the heat of combustion going on in the lower layers of fuel. Probably every household furnace attendant has noticed the escape of furnace gas from 55 the heating device or its smoke flue, immediately after a fresh feeding of coal fuel.

These gases usually escape into the chimney more or less unconsumed, which loss would not occur if the fuel-gas were more frequently or more continuously fed and maintained at a thinner depth. The ordinary method of "banking" fires with wet or dry ashes, has the disadvantage of clogging the fuel mass with ashes preventing combustion of the fuel surrounding the interstices 60 clogged by the ashes, that must be removed downwardly through the fuel-mass at the cost of labor and a delay in heating effect when a quick increase in and transmission of heat is desired. Also that old practice excludes the possibility of having through automatic action occurring in the fuel mass, in place and already in a satisfactory glowing state of combustion and radiating intense heat effectively, a full supply of still burnable fuel not clogged with an admixture of 65 ashes, in the early morning hours when heat in the household as a matter of physical comfort is very desirable.

I overcome old-time defective practice in 70 this connection, by the simple method of blanketing or banking the top of the fuel-mass, when a diminution of the rate of combustion is required, with an ash-free fuel of finer particles than the fuel that comprises 75 the major part of the fuel-mass. It is customary to use fuel having a size as to its particles that will presumably allow for a desirable proportion of air for combustion passing through the fuel-mass; and by various methods of stoking, to free the ignited 80 and partly-burned particles of fuel from the ashes of combustion by grate shaking, or otherwise.

In my method, in providing for the over-night treatment of the fuel-mass, instead of waiting until the morning to eliminate the ashes from the fuel-mass, I free it from 85 ashes, at the time of its last stoking in the evening, so much as will leave a substantially entirely free passage of air through the fuel mass when an automatic accession 90 of the rate of combustion desired is resumed, and temporarily check the rate of combustion without changing the draft controlling 95 structures of the heating device, by then spreading a layer of unburned fuel of such small size as to its particles as will largely close up the air apertures between the larger 100 fuel particles at the upper level of the fuel- 105 mass, in a blanket-coat of moderate though sufficient thickness, of the finer-sized fuel to 110

temporarily suspend combustion in the fuel. The selected thickness of the blanket-coat is proportionate to the time of desired reduction in the rate of combustion. This procedure produces the immediate effect of largely preventing the passage of air upwardly through the fuel-mass, or of air passing downwardly between the ignited fuel particles from the combustion space above the fuel-mass. But the heat in the ignited fuel gradually heats the blanketing fine fuel coat and drives off its volatile constituents; and thus automatically, gradually renders the blanketing coat more porous and passable for air for combustion. The result of this practice is that while a very considerable amount of fuel is not burned during the sleeping hours of the household, during those hours the upper part of the fuel mass gradually attains an effective condition of active heat radiation; the volatile matters having been driven off slowly and mostly burned, while the coked residue is in a condition for securing its entire combustion *in situ* immediately at the upper level of the fuel-mass, without having a considerably large amount of its gaseous burnable constituents conveyed into the chimney in the form of unburned carbon-monoxide and other gases. This condition of effective heat radiation is automatically secured for the early hours of the day when the comfort of the members of the home is dependent on a warm house atmosphere. This secured effect also avoids the necessity of feeding at one time a large amount of fuel in the early day and then forcing the draft to increase the rate of combustion in order to get heat in the house as soon as possible, and under which management it takes considerable time to get the newly fed fuel into an effective condition of combustion, and in which there is a large loss of transmission efficiency through air dilution by the enforced draft with consequent reduction in the temperature of the heating gases, as well as decrease in the temperature at which ignition occurs. Also, the heating gases being drawn over the heating surfaces very quickly, and being of a relatively low temperature, there is a lessened transmission of the heat that is generated in the combustion chamber of the heating device. It will be understood that in carrying out my process I continue the introduction of a proper amount of air for combustion to secure the burning of any evolved combustible gases both through and above the fuel mass, yet avoid introducing sufficient air to act in unduly cooling the burning gases.

I estimate that the saving in fuel consumption through the practice of this method alone, will be nearly one-fifth of the fuel costs of ordinary household heating.

65 More than one-half of the bulk of ashes

resulting from the use of anthracite fuel in dwelling houses, is composed of unburned carbon from which tar and sulfur and other volatile matters have been driven by heat. This unburned carbon can be used for the 70 purpose of my method, through wetting them and admixing them with fine dust-like anthracite, bituminous and lignite fuels, or coke-breeze. It is obvious that the softer fuels can be first coked and then used in 75 this way incidentally producing liquid by-products and burnable gas of value while the coke, moistened with water, and admixed with some fine coal dust or slack, which will adhere to the moistened coke, makes an excellent low-cost blanketing material to use for my purpose. It will be noted that wetting the porous coked particles, temporarily closes the air passages of those particles and thus prevents the passage of air for combustion through the coked fuel particles. But as the underlying heat drives off the moisture the draft is automatically re-established through them, and the fine adherent dust attached to the coked fuel is volatilized; 80 after which a glowing fuel bed surface will have been developed automatically, very effective in its power to radiate heat.

This method used with effective methods for the diffused introduction of air for combustion over the fuel mass, and preferably introduced at a point close to the point of exit for the gases of combustion from the combustion chamber, as indicated in patents issued to me, directly and indirectly 95 will cut the fuel costs of heating fully 100 per cent. in ordinary house-heating, and through the use of the heating devices generally in use.

It will be noted that instead of my decreasing the rate of combustion by choking the air spaces in the fuel mass with ashes, I substitute a temporary banking and a succeeding slowing of the rate of combustion, but maintain a rate that automatically progressively increases in rapidity, and without change in the position of the draft structures of the heating device. In this way I secure an economical burning of fuel and a better transmission into the house, of the developed heat. There is no economy in cooling off a dwelling-house at night, so far as fuel conservation alone is concerned, if a wasteful rate of combustion in the early hours of the day must be practised to quickly again heat 110 up the house in those hours. Hence will be seen the value of an intermittent lessened rate of combustion and the effectuation of a more equalized rate in the burning of the fuel, under the stated conditions.

In the ordinary methods of burning fuel through infrequent fuel feedings, there is a continually decreasing rate of combustion and an undesirable too greatly consumed condition of the fuel-mass for nearly half 125 130

of each twenty-four hours. But with my method there is automatically effectuated a progressive increasing rate of combustion and a satisfactory state of the fuel-mass at 5 the time of day when that condition is particularly desirable. The differentiation of my process from the old procedure of banking the fire is further elucidated in the following claims.

10 The invention herein claimed is based on the following named discoveries, viz., that if at the usual hour of retiring to bed, the fuel mass in the furnace of a house heater is freed from ashes and is replenished by 15 a blanketing coat of suitable thickness on the entire upper surface of the fuel mass, of an ash free fuel of finer particles than the sub-situated larger fuel particles of the fuel mass; and if the blanketing coat is of a 20 nature that will allow some upwardly travel of gases therethrough and that will maintain a more or less porous character, and that will allow a progressively increasing flow of gases through the blanketing coat; 25 and if the draft regulation from below upward through the fuel mass is not cut off, and if there is a maintained diffused introduction of a proper amount of air over and above the fuel mass to secure a substantially 30 complete combustion of the unburned gases rising from the fuel mass and its blanketing coat; the following hitherto unrecognized phenomena will occur:

1st. At the usual morning hour of rising 35 from bed of the members of the household, the upper surface of the fuel mass in the furnace will be in a brilliant state of smokeless incandescence and active heat radiation that secures a very positive transmission of 40 the heat generated from the fuel, through the heating surfaces of the heater.

2nd. That the room temperature of the house will have been automatically effect- 45 ively maintained and increased to a com- fortable degree.

3rd. That the usual extent of burning of the fuel mass has not occurred, and that hence it is not necessary to increase in the morning, the rate of combustion in the furnace to secure a quick replenishment of the 50 heat in the house; and

4th. That a considerable saving in the cost of house heating is secured. This discovery on my part entitles me to patent protection for the use of the method and its sub- 55 sidiary acts when used for the purpose and as herein described.

Subject matter is disclosed in this case that will be claimed in separate applica- 60 tions.

What I claim as new is:

1. The method herein described, which consists in, filling air spaces in coked fuel with water, admixing with and coating the wet coked fuel with an uncoked fuel dust; 65 and applying a blanketing coat of the admixed fuel to an ignited fuel-mass.

2. The method herein described, which consists in, blanketing and thus temporarily banking an ignited fuel-mass with a 70 horizontally applied coating to the substantially entire upper surface of an ignited fuel-mass of an admixture of moistened porous coked fuel and an ash free fuel dust.

3. The method herein described, which consists in temporarily blanketing a fuel mass in a state of ignition with a banking coat of moistened cinders having adhering ash free coal dust, said adherence being in- 75 creased by the moisture in the cinders. 80

JOSEPH MOSES WARD KITCHEN.
